WILLIAM CRELLIN PICKERSGILL, OF PROVIDENCE, RHODE ISLAND.

Letters Patent No. 81,679, dated September 1, 1868.

IMPROVEMENT IN BOILER-FEEDERS.

The Schedule referred to in these Letters Patent and making part of the same.

TO ALL WHOM IT MAY CONCERN:

Be it known that I, WILLIAM CRELLIN PICKERSGILL, of the city and county of Providence, in the State of Rhode Island, have invented certain new and useful Improvements in Automatic Boiler-Feeders; and I do hereby declare that the following specification, taken in connection with the drawings making a part of the same, is a full, clear, and exact description thereof.

Figure 1 is a view of my improved feeder in elevation.

Figure 2 is a side view of the same.

Figure 3 shows another form of construction.

The object of my invention is to produce a vessel which, by means of a steam-cylinder and certain mechanism, shall receive from the tank and furnish to the boiler a steady, regular, and sufficient supply of water.

I am aware that many inventions have, of late, been made in automatic boiler-feeders, which, in many respects, resemble the one I am now about to describe, yet none, however, have employed a steam-cylinder, which I deem indispensably necessary to the successful operation of this class of inventions, the use of which, for such purpose, is more particularly the subject of this patent.

In the drawings—

A, fig. 1, is a water and steam-chamber, into which the water flows from the supply-tank, through the supply-pipe N, in which is placed a valve, J, opening inwards.

B is a float, of wood or hollow metal, which moves up and down upon the rod C, between the collars e and f.

The rod C is connected with the lever D upon the top of the vessel, which is, in turn, connected by the valve-rod E to the steam-valve F and steam-cylinder G, the piston-rod of which is connected by means of levers, and operates the cocks H and I alternately, connecting the vessel A with supply-tank and boiler at water-level; the levers and rod being shown by blue lines, fig. 1.

The vessel A occupying a position higher than the water-level of the boiler, and lower than the supply-tank, the operation of the feeder is as follows:

Commencing with the vessel A, filled with steam, and connected with the boiler by the pipe L, the cock H being open, and the float B resting upon the collar f, having, by its weight, just pressed down the rod C, which has in turn carried down the lever D, and admitted the steam, by means of the valve F, into the cylinder G. As soon as the steam enters the cylinder G, the piston being connected with the levers a and b, moves them suddenly towards the left, until they assume an angle corresponding to that represented by the blue lines, thus instantly closing the cock H, and opening the cock I.

The vessel A is now connected with the supply-tank only, and being full of steam, the cold water coming in through the pipe M condenses the steam, and a vacuum is formed. The pressure from the supply-tank now opens the valve J, and allows the water to flow into the vessel A, which raises the float B until it reaches the collar E, when it moves upwards the rod C, and also the lever D. The steam is again admitted to the cylinder G, and the levers a and b are moved back, and occupy the position shown in fig. 1, and the vessel A is now connected with the boiler only, the vacuum is destroyed, and the water, by its own gravity, opens the valve K, and flows into the boiler. The float B descends until it reaches the collar f, when the same operation is repeated.

I have thus described the operation of the entire machine, in order that I might more clearly show the improvements hereinafter claimed.

In other inventions of this class, where a steam-cylinder has not been employed, the float has usually been attached to the rod passing through the chamber A, and moves the rod up and down as the water rises and falls, so that the friction of the rod in the stuffing-boxes at each end of the vessel A is constant.

Again, the rod passing through the vessel A being connected (in many other inventions of this class) directly with the levers which move the cocks, the alternate connection of the vessel A with the boiler and supply-tank will be gradual, as the water rises and falls, and not instantaneous, as in feeders, where the float operates a steam-valve and cylinder.

It will now be readily seen that at certain periods the automatic operation of the feeder must be suspended; for instance, as the float moves downward, the cock which connects the vessel A with the boiler closes gradually, and must become entirely closed before the cock connecting it with the supply-tank opens, otherwise the steam would blow through and the machine stop. As soon as the cock connecting with the boiler is closed, the gravity of the water is overcome, and the float arrested in its downward progress before it has descended far enough to open the cock connecting with the supply-tank, and the machine must, in this case, stop.

In my invention these difficulties are overcome by the use of a steam-cylinder, as will be seen from the foregoing description, the float merely operating a steam-valve.

What I claim as my invention, and desire to secure by Letters Patent, is—
The combination of the float B, rod C, lever D, with the steam-valve F, steam-cylinder G, and cocks H and I, substantially as and for the purposes set forth.

WILLIAM CRELLIN PICKERSGILL.
